UNITED STATES PATENT OFFICE.

GEORGE WALTER NORRAGE, OF CHICAGO, ILLINOIS, ASSIGNOR TO BENJAMIN ELECTRIC MANUFACTURING COMPANY, OF CHICAGO, ILLINOIS, A CORPORATION OF ILLINOIS.

ATTACHMENT-PLUG.

1,287,082.

Specification of Letters Patent. Patented Dec. 10, 1918.

Application filed December 28, 1914. Serial No. 879,247.

To all whom it may concern:

Be it known that I, GEORGE WALTER NORRAGE, a citizen of the United States, residing at Chicago, in the county of Cook and

5 State of Illinois, have invented new and useful Improvements in Attachment-Plugs, of which the following is a full, clear, concise, and exact description, reference being had to the accompanying drawing, forming

10 a part of this specification.

My invention relates to attachment plugs, and specifically to the type of plug shown in my co-pending application, Serial No. 847,385, filed June 26, 1914, in which an in-

15 sertible member is provided with a spring coil surrounding it which may be forced into engagement with the threads of the shell contact of the lamp socket.

One of the objects of my invention is to 20 simplify the construction of plugs of this character and increase the efficiency.

Further objects will appear from the detailed description to follow.

In the accompanying drawings in which 25 I have illustrated one embodiment of my invention—

Figure 1 is an axial section through my improved plug, showing the manner in which it engages the lamp socket, and showing 30 the spring ring expanded into engagement with the threaded contact of the socket;

Fig. 2 is a section similar to Fig. 1 showing the cam disengaged from the spring ring and the spring ring in contracted position;

Fig. 3 is a section on the line 3—4 of Fig. 1 showing the spring ring disengaged from the threaded contact;

40 Fig. 4 is a similar section showing the spring ring engaging the contact;

Fig. 5 is a perspective view of a flanged retaining member showing the helical shoulder for holding the spring ring in place;

45 Fig. 6 is a perspective view of the shell member which supports the spring coil showing the helical shoulder on which the spring coil rests;

Fig. 7 is a perspective view of a sleeve 50 member provided with cam projections for engaging the spring coil;

Fig. 8 is a perspective view of an insulating base forming a support for the shoul-

Fig. 9 is a perspective view of the spring 65 coil; and

Fig. 10 is an elevation of the spring coil showing the relation of the ends of the coil to each other.

Referring now to the drawing in detail, 60 reference character 11 indicates in general a lamp socket comprising an outer metal casing 12, a sleeve 13 of insulating material such as fiber, and a threaded shell contact

14 insulated from the casing 12 by means 65 of the sleeve 13. The plug itself comprises an insertible portion indicated in general by 15 and a binding terminal carrying member, indicated in general by 16, which also car-

ries the cam for actuating the spring coil. 70 The insertible portion 15 comprises a shell 17 of sheet metal, preferably a brass stamp-

ing, a flanged retaining member 18 which also may be a brass stamping, an insulating cap 19, an insulating base 20, and a hollow 75 rivet 21 extending through the base 20 and cap 19 to hold the parts of the insertible portion together. The hollow rivet 21 also

forms the center contact of the plug which engages the center contact 21^a of the lamp 80 socket. The shell 17 is reduced to form a helical shoulder at 22 on which the spring coil rests, and has an inwardly extending flange 24 for engagement with a similar flange on the retaining member 18. The 85

shoulder 22 has a number of slots 25 through which the cam members which actuate the spring coil project. The retaining member 18 has its lower end shaped to form a helical shoulder 26 for engagement with the spring 90

coil to hold the latter in position. The retaining member also has an inwardly ex- 95

tending flange 27 for engagement with the flange 24 on the shell 17. The insulating base 20 has its upper end reduced as at 28 95

to allow it to pass through openings in the shell 17 and retaining member 18. A spring coil 29 rests on the helical shoulder 22 and is held in place thereon by its en-

gagement with the shoulder 26 on the re- 100

taining member 18.

The binding terminal carrying member 16 comprises a contact shell 30 which is pro- 105

vided with cam projections for engagement with the spring coil, an insulating base 31 and a cord supporting shell 32 of sheet metal, preferably brass, which also forms a hand grip for inserting the plug in the

socket. The contact shell 30 has a number of upwardly projecting cam members 33 which extend through the openings 25 in the shell 17 and are provided with cam surfaces 34 for engagement with the spring coil 29. A pin 35, secured in the shell 30 and base 31 in any suitable manner, engages a slot 36 in the shell 17 to limit the sliding movement of the binding terminal carrying member 10 with respect to the insertible portion 15. A contact plate 37 embedded in the insulating base 31 is provided with a binding screw 38 and is secured to the contact shell 30 in any suitable manner as by a rivet 39. A binding plate 40 also embedded in the insulating base 31 is provided with a binding screw 41 and is connected by means of a rivet 42 with a contact member 43 (which may be a split pin) which engages the center contact 21 20 of the insertible portion. The cord supporting shell 32 is provided with a threaded portion 44 for engagement with a correspondingly threaded portion on the base 31. Within the shell 32 is a cup shaped insulating member 45 of any suitable material, such as fiber. The conductors connected to the binding posts 38 and 41 are knotted together, as shown at 46, so that a pull on the conductors will not transmit a strain on the binding posts but will be taken care of by the shell 32.

The operation of my improved device is as follows: Assuming that the parts are in the position shown in Fig. 2 in which the cams 33 are disengaged from the spring coil 29 and the latter is in its contracted position, the insertible portion 15 of the plug is introduced within the lamp socket 11 until the center contact 21 on the plug engages the center contact 21^a on the socket. As soon as the contact 21 comes solidly into engagement with the contact 21^a further inward pressure on the plug will cause the shell 30 to telescope within the shell 17 and the cam 40 faces 34 to come into engagement with the spring coil 29 to force the latter outwardly into engagement with the threads of the shell contact 14. In case the spring coil 29 is not in just the right position to engage 45 the threads on the shell contact 14 the plug is rotated slightly in one direction or the other until the parts are in just the right position.

It will be noted that this plug is so constructed that when a pull is exerted on the conductors secured to the binding terminals 38 and 41 the cam members 33 will be withdrawn from engagement with the spring coil 29 permitting the latter to contract so 50 that the plug may be withdrawn from the socket. The electrical connection between the center contact 21^a of the socket and the binding post 41 is through the hollow rivet 21, the split pin 43 which slidably engages the contact 21, the rivet 42, and the contact plate

40. The electrical connection between the threaded shell contact 14 of the socket and the binding terminal 38 is through the spring coil 29, the shell 17, the contact shell 30, the rivet 39 and the binding plate 37. 70

Having thus described my invention what I claim as new and desire to secure by Letters Patent is;

1. An attachment plug including an insertible member, a helical spring surrounding said member of a size and shape to engage the threads of a lamp socket, and means movable axially with respect to the plug for forcing said spring into contact with said socket, said member being provided with 80 means for preventing endwise movement of said spring thereon in either direction. 75

2. An attachment plug including an insertible member comprising a shell having a helical shoulder, and a retaining member 85 secured to said shell, and having a helical shoulder adjacent said first shoulder, and a helical spring held in place between said shoulders.

3. An attachment plug including an insertible member comprising a shell having a helical shoulder provided with a slot, a helical spring engaging said shoulder, and cam means extending through said slot to engage said spring. 90

4. An attachment plug including an insertible member comprising a shell having a helical shoulder and an inwardly extending flange, and a retaining member secured to said shell and having a helical shoulder 100 and an inwardly extending flange adjacent said first flange, and a helical spring held in place between said shoulders, an insulating base engaging the shell flange, an insulating cap engaging the other flange, and means for securing said insulating base and cap together to hold the flanges therebetween. 105

5. An attachment plug including an insertible member comprising a shell having a helical shoulder and an inwardly extending flange, and a retaining member secured to said shell and having a helical shoulder and an inwardly extending flange adjacent 110 said first flange, a helical spring held in place between said shoulders, an insulating base engaging the shell flange, an insulating cap engaging the other flange, and a center contact for securing said insulating base and cap together to hold the flanges therebetween. 115

6. An attachment plug including an insertible member comprising a shell having a helical shoulder and an inwardly extending flange, and a retaining member secured to said shell and having a helical shoulder 120 and an inwardly extending flange adjacent said first flange, a helical spring held in place between said shoulders, an insulating base engaging the shell flange, an insulating cap engaging the other flange, and a hollow 125

rivet forming a center contact for securing said insulating base and cap together to hold the flanges therebetween.

7. A plug comprising an insulating base, 5 a contact supported by said base and movable with respect thereto into and out of engagement with the threaded contact of a receptacle, retaining means for holding said movable contact in engagement with the 10 threaded contact, a flexible conductor electrically connected with said movable contact

and mechanically connected with said plug, and means whereby a pull on said conductor will cause said retaining means to release said movable contact.

15

In witness whereof I have hereunto subscribed my name in the presence of two witnesses.

GEORGE WALTER NORGATE.
